(57) **CLAIM**

We claim:

The ornamental design for a lid for beverage container, as shown and described.

DESCRIPTION

FIG. 1 is a perspective view of a lid for beverage container according to our new design;

FIG. 2 is a rear view of the lid for beverage container shown in FIG. 1;

FIG. 3 is a left side view of the lid for beverage container shown in FIG. 1;

FIG. 4 is a front view of the lid for beverage container shown in FIG. 1;

FIG. 5 is a right side view of the lid for beverage container shown in FIG. 1;

FIG. 6 is a top view of the lid for beverage container shown in FIG. 1;

FIG. 7 is a bottom view of the lid for beverage container shown in FIG. 1;

FIG. 8 is a perspective view of a lid for beverage container showing a second embodiment of our new design having a rotatable handle;

FIG. 9 is a rear view of the lid for beverage container shown in FIG. 8;

FIG. 10 is a left side view of the lid for beverage container shown in FIG. 8;

FIG. 11 is a front view of the lid for beverage container shown in FIG. 8;

FIG. 12 is a right side view of the lid for beverage container shown in FIG. 8;

FIG. 13 is a top view of the lid for beverage container shown in FIG. 8; and,

FIG. 14 is a bottom view of the lid for beverage container shown in FIG. 8.

The broken lines in the drawings are included for the purpose of illustration and form no part of the claimed design.
